(**) Term: **14 Years**

(57) **CLAIM**

(21) Appl. No.: **29/266,549**

The ornamental design for a carbon monoxide detector for automatically opening garage doors, as shown and described.

(22) Filed: **Sep. 25, 2006**

DESCRIPTION

(51) **LOC (8) Cl. 10-04**

(52) **U.S. Cl. D10/81**

(58) **Field of Classification Search** D10/81; 340/628, 629, 630, 632, 633, 634, 527; 454/239, 454/256, 343

See application file for complete search history.

FIG. 1 is a front elevation view of a carbon monoxide detector for automatically opening garage doors showing my new design;

FIG. 2 is a rear elevation view;

FIG. 3 is a right elevation view;

FIG. 4 is a left elevation view;

FIG. 5 is a top plan view;

FIG. 6 is a bottom plan view; and,

FIG. 7 is an isometric view of a carbon monoxide detector for automatically opening garage doors showing my new design.
